UNITED STATES PATENT OFFICE.

EDWARD EMMETT HENDERSON, OF HALLOWELL, KANSAS.

AEROPLANE GUIDING AND BOMB-DROPPING APPLIANCE.

1,294,907.

Specification of Letters Patent. Patented Feb. 18, 1919.

Application filed December 26, 1917. Serial No. 209,007.

To all whom it may concern:

Be it known that I, EDWARD E. HENDERSON, a citizen of the United States, and a resident of Hallowell, in the county of 5 Cherokee and State of Kansas, have invented a new and Improved Aeroplane Guiding and Bomb-Dropping Appliance, of which the following is a full, clear, and exact description.

10 This invention relates to an appliance for aeroplanes whereby an observer can communicate to his pilot, by an indicating device, the manner of guiding the aeroplane for bombing or photographing any target 15 or other selected place, the apparatus including a telescope sight which the observer maintains on the target and thereby operates an indicating device which is conveniently positioned to the pilot so that he can steer 20 the aeroplane in the proper course.

The invention has for its general objects to provide an apparatus of this character which is reliable and efficient in use, easily manipulated and of durable and compact 25 design.

A more specific object of the invention is the provision of a sighting device mounted to swing on a vertical or horizontal axis so that any desired target can be sighted, 30 and by suitable transmitting means leading from the telescoping sight to a pilot's indicator the movable element of the latter can be actuated in synchronism with the movable sight and thereby reveal to the pilot 35 the direction he is to steer for bringing the airship to a point over the target where bombs can be accurately dropped or photographs taken.

Another object of the invention is to provide 40 means for automatically controlling the dropping of a bomb or taking of a photograph when the telescope sight reaches a certain angle in pointing downwardly on the target.

45 With such objects in view, and others which will appear as the description proceeds, the invention comprises various novel features of construction and arrangement of parts which will be set forth with particularity in the following description and claims appended hereto.

In the accompanying drawings, which 50 illustrate one embodiment of the invention and wherein similar characters of reference indicate corresponding parts in all the views,

Figure 1 is a front view of the observer's telescope sighting apparatus with a telescope sight pointing downwardly and the gimbal yoke in section; 60

Fig. 2 is a side view with portions in section;

Fig. 3 is a detail sectional view on the line 3—3, Fig. 1;

Fig. 4 is a central vertical section of the 65 head in which the telescope sight shaft is mounted;

Fig. 5 is a view of the switch end of the head;

Fig. 6 is a sectional view showing the 70 details of the automatic switch;

Fig. 7 is a diagrammatic plan view of the apparatus as installed on an aeroplane;

Fig. 8 is a view of the outer end of the telescope sight and the leveling device 75 thereon;

Fig. 9 is a diagrammatic view showing 80 an aeroplane in several different positions in its approach to a target when guided by the observer's sighting device.

Referring to the drawing, A, Fig. 7, designates a sighting apparatus adapted to be used by an observer on an aeroplane, B an indicator arranged within the view of and adjacent to the pilot so as to enable him to 85 steer the flying machine to the target or object the observer is sighting; and associated with the apparatus A is a switch C for controlling electric circuits for dropping bombs or taking photographs at successive times when the sighting device is in a predetermined position with respect to the object or target. D indicates the system of cable connections between the apparatus A and the indicator B, whereby the motion 90 of the sighting telescope or the position thereof can control the indicator to properly guide the pilot to the target.

The apparatus A comprises a pair of stationary standards 1 mounted upon a suitable 100 base support 2, and each having at its upper end a stationary journal 3 that carries a horizontally disposed gimbal yoke 4 that is in the form of an open frame having its ends 5 provided with journal-receiving openings 105

6. Suspended from the side members 7 of the frame 4 is a perpendicular-like body or pendant member 8 having, at its top ears 9 for connection with the frame 4. This member 8 forms a support or bearing for a vertical shaft 10 on which the head 11 swings in a horizontal plane. The head 11

is disposed above the yoke or frame 8, and axially disposed in the head is a horizontal shaft 12 arranged at right-angles to the shaft 10 and carrying the cradle frame 13 on which the telescope sight 14 is mounted. By reason of this disposition of the shafts 10 and 12 the telescope sight can swing in a vertical plane or in a horizontal plane, or in planes intermediate these two, so that the sight can be pointed in any direction, and by reason of the gimbal frame 4 it is possible to maintain the shaft 12 always in a horizontal plane, even though the aeroplane be tilted.

15 To facilitate the leveling of the telescope sight a spirit level 15 is carried by the outer end of the sight 14, as clearly shown in Figs. 1 and 8, there being a bracket or horizontally extending arm 16 on the sight to adjustably support the holder 17 for the spirit level. By means of a set-screw 18 the spirit level can be moved inwardly or outwardly so that the central index line 19 will, by reason of double vision, coincide with the vertical one 25 of the crossing hair lines 20 of the sight, this relation being indicated by the dotted outline of the spirit level, Fig. 8.

The swivel head 11 comprises a stationary tubular portion 21, to which the shaft 10 is rigidly fastened, and on this portion 21 are caps 22 and 23, the former being rotatable and the latter stationary. The head 22 includes a porcelain or other insulating part 24 which forms a support for the parts of the 30 automatic switch which is located within the head 11. The shaft 12 rotates in the caps and turns in only one direction by reason of a ratchet wheel 25 on the shaft and a spring-pressed pawl 26 on the cap 23, as shown in 40 Figs. 3 and 4.

The automatic switch in the head 11 comprises a fixed contact 27 and a movable contact 28 fulcrumed at 29 on the insulating support 24, which latter is fastened to the 45 cylindrical part 30 of the cap 22 by bolts 31 which pass through an internal annular flange 32 of the sleeve 30 and through the insulating support 24. On the shaft 12 is a cam 33 which engages the tooth 34 of the 50 movable contact 28 and holds the latter raised until the tooth 34 drops off the high part of the cam 33, when the contacts 27 and 28 will be engaged to close an electric circuit that controls an electric release for a bomb-dropping device or an electrically-operated device of a cam. The time at which the cam 33 will permit the circuit to close is determined with respect to the declination of the telescope sight 14, and this angle of inclination 55 can be adjusted by the aid of a scale 34 on the fixed part 21 of the head 11 and an index 35 carried by the rotatably adjustable cap 22. By adjusting the cap with respect to the scale the position of the movable contact 28 with respect to the cam 33 can be va-

ried. In arriving at the proper adjustment it is necessary to consider the speed of travel of the aeroplane and its altitude with respect to the target, so that the bomb will be released at a proper time before the target is 70 reached, to cause the bomb to travel on the right curve in dropping upon the target.

The indicating device B comprises a dial 36 which is fixed on the aeroplane frame at a point within convenient view of the pilot, 75 and over this index moves a hand 37 which is operatively connected with the head 11 so that the swing of the telescope sight in a horizontal plane or on a vertical axis will cause the hand 37 to change with respect to 80 the index cross 38, the operative connection being brought about by means of the transmission system D. On the vertical shaft 10 of the apparatus A, or connected with the head 11, is a pulley 39 to which is fastened 85 an endless cable 40 that runs through a passage 41 in one of the journals 3, as shown in Fig. 2, there being suitably arranged guide pulleys 42 and 43 for guiding the cable. The cable 40 extends laterally from the apparatus A, as shown in Fig. 7, and passes around a pulley 44, and from this pulley 44 extends another endless cable 45 which passes around a pulley 46 connected with the needle 37 on the indicator B.

The contacts 27 and 28 of the automatic switch are connected with wires 47 and 48, which, for convenience, pass through the pendant member 8 and run therefrom through the journal 3 opposite from that 95 through which passes the cable 40, the wires being connected with an observer's controlling switch 49 which is connected in any suitable manner with electrically-operated bomb-releasing devices 50 suggested, but not 100 shown in detail. The movable contact switch 49 is movable successively to different positions for dropping the successive bombs, one bomb being dropped at a time when the telescoping sight is sighted on an object and is 110 in the proper angle of inclination. After a bomb is dropped the switch 49 is moved to bring the next bomb-releasing device into 115 operative condition so that when the telescope sight is again used the second bomb will be dropped, and so on.

In using the apparatus the observer manipulates the sight 14 with one hand to hold it trained on a target, and with the other hand he moves the pendant member 8 to keep the telescope level by means of the spirit level 15.

In Fig. 9, E represents a target and F represents an aeroplane which is shown in four different positions, a, b, c, d, approaching the target. At position a the observer sights the apparatus A against the target, which causes the indicating needle 37 to assume a position parallel with the telescope sight 14. The pilot noting the position 120

of the indicating needle 37 with respect to the cross 38 steers the aeroplane in one direction or the other to bring the hand 37 back to the cross 38. The steering of the aeroplane 5 does not cause the needle 37 to shift, but the observer by maintaining the sighting device trained on the target causes the indicating needle to move with respect to the cross 38 as the body of the aeroplane shifts. In positions *b*, *c*, and *d* it will be noted that the aeroplane is heading more and more toward the target and the needle 37 approaches nearer and nearer to the index cross 38, and as the aeroplane is headed directly at the target the 10 sighting device is pointed more and more toward a perpendicular position, until finally the electric switch closes to cause a bomb to be dropped or a picture to be taken. Fig. 9 shows the airship being steered to the left, 15 but the apparatus works in a similar manner when the steering is to the right.

From the foregoing description taken in connection with the accompanying drawings, the advantages of the construction and 20 method of operation will be readily understood by those skilled in the art to which the invention appertains, and while I have described the principle of operation, together with the apparatus which I now consider to 25 be the best embodiment thereof, I desire to have it understood that the apparatus shown is merely illustrative and that such changes may be made when desired as fall within the scope of the appended claims.

35 Having thus described my invention, I claim as new and desire to secure by Letters Patent:

1. An apparatus for signaling between an observer and a pilot of an aeroplane, comprising an observer's sighting device, means for mounting the device to point in any direction, an indicator for guiding the pilot in steering and including a movable element, means for actuating the element by the 40 movement of the sighting device laterally in either direction, and means automatically set off by the movement of the sighting device when the aeroplane is in a predetermined position with respect to an object sighted for 45 photographing or bombing such object.

2. An apparatus of the class described comprising an observer's sighting device, means for mounting the device to turn on a horizontal axis, means for mounting the device to turn on a vertical axis, a pilot's indicator for guidance in steering, said indicator 50

including a dial and movable element, and motion-transmitting means between the second-mentioned means and movable element, whereby the swinging of the sighting device on a vertical axis operates the said element. 60

3. An apparatus of the class described comprising an observer's sighting device, means for mounting the device to turn on a horizontal axis, means for mounting the device to turn on a vertical axis, a pilot's indicator for guidance in steering, said indicator including a dial and movable element, motion-transmitting means between the second-mentioned means and movable element, whereby the swinging of the sighting device on a vertical axis operates the said element, and an electric switch associated with the device for affecting a controlling circuit 75 when the sighting device is moved to a predetermined angle of inclination.

4. An apparatus of the class described comprising an observer's sighting device, a vertical shaft on which the device is mounted, 80 a head in which the shaft is rotatably mounted, a supporting structure on which the head is mounted to turn on a vertical axis, a pilot's indicating device including a movable element for assisting in steering, 85 and a cable and pulley system between the said head and the movable element, whereby the movement of the head moves the latter.

5. An apparatus of the class described comprising a head, a frame mounted to 90 swing on a horizontal axis, means for mounting the head to turn on a vertical axis, a sighting device carried by the head to turn on a horizontal axis, a level connected with the sighting device, a pilot's indicator including a movable element, and means for actuating the element by the movement of the head on its turning axis. 95

6. An apparatus of the class described comprising a plurality of supports, a frame journaled on the supports to swing on a horizontal axis, a pendant member carried by the frame, a head pivoted on the member to turn in a vertical plane, an observer's sighting device pivotally mounted on the head 100 to turn on a horizontal axis, a pilot's indicating device for assisting the steering and including a movable element, and means actuating the movable element by the movement of the head on its vertical axis. 105

EDWARD EMMETT HENDERSON.
